I. B. WINSOR

DEEP WELL PUMP

Filed July 24, 1924

UNITED STATES PATENT OFFICE.

IRWIN B. WINSOR, OF LOS ANGELES, CALIFORNIA, ASSIGNOR TO SINGER PUMP COMPANY, A CORPORATION OF DELAWARE.

DEEP-WELL PUMP.

Application filed July 24, 1924. Serial No. 728,044.

My invention relates to deep well pumps and pertains more particularly to deep well pumps for pumping oil.

The principal object of the invention is to 5 provide a pump in which slippage is greatly reduced.

Another object of the invention is to provide a pump in which the surface tension and viscosity of crude oil are employed in 10 reducing slippage.

In conformance with other objects, my invention contemplates the use of a plunger which may be withdrawn through the tubing for inspection, repair or replacement, and 15 it is, therefore, another object of the invention to provide a construction whereby the plunger will readily center itself properly on being returned to the pump barrel.

Another object of the invention is to provide 20 a pump in which metal-to-metal contact between reciprocating and stationary parts is obviated as much as possible, it being my intention to keep a film of oil around the plunger at all times as a seal, and it is, 25 therefore, another object to provide for the plunger automatically centering itself with regard to other parts of the pump so that the sealing film is continuous and uniform circumferentially of the plunger.

It will be understood that in oil well 30 pumps of the more common type the upward stroke of the plunger might be termed both the discharge and suction stroke, while during the downward stroke the oil column is 35 motionless. It is during the upward stroke that the pressure within the plunger between the standing valve and the working valve is negative. It is at this time that the hydrostatic pressure of the oil column, which reaches to the surface, acts to force oil back 40 past the clearance of the plunger and into the plunger again. This reverse flow or slippage I propose to overcome by so arranging the parts that the hydrostatic pressure is not transmitted to the film of oil 45 immediately surrounding the plunger.

It will be obvious, particularly hereinafter, that if I prevent return flow or slippage through the plunger clearance, I will, therefore, reduce the tendency of sand to be carried into said clearance during the up-stroke or lift of the pump.

It is also a recognized fact that in pumps of the above mentioned type the down-stroke

sets up an increased pressure between the 55 two valves. Said increased pressure is due to the fact that the plunger tries to descend more rapidly than the oil can flow upwardly through the working valve. Such back pressure causes a slight leakage upwardly around 60 the plunger, and such flow will act to encourage sand finding its way into the clearance.

It is, therefore, another highly important 65 object of the invention to provide a pressure balancing effect around the plunger so that such slippage is either reduced or eliminated so that sand will be discouraged from entering the clearance immediately surrounding 70 the plunger.

While sand may be kept from the plunger and relatively moving parts, it will, however, tend to settle around the standing valve and 75 it is, therefore, another object of my invention to provide a pump barrel and standing valve construction whereby the act of lifting the standing valve will result in the pump automatically cleansing itself of sand accumulations.

Another object of the invention is to provide 80 a pump in which the standing valve may be raised through the tubing.

Another object of the invention is to provide 85 a standing valve assembly which may be effectively anchored down in the pump barrel and in which the hydrostatic pressure of the oil column extending therefrom to the surface will act to assist in holding the valve assembly in place during the up-stroke 90 of the plunger.

Still another object of my invention is to provide a construction in hollow-plunger, direct-flow single acting pumps which will reduce the possibility of the plunger working in, or producing, a gas pocket without displacing any oil.

Many other objects and advantages of my improved pump will appear hereinafter, and they will be better understood by virtue of 100 the order of their occurrence hereinafter.

I have illustrated by the accompanying drawings one embodiment of my invention, and by reference to the drawings and following description of the construction and operation of its parts, those skilled in the art 105 will be enabled to make and use the pump and employ, in this or other embodiments of my invention, or in other pumps, the

scientific principles which I have discovered and applied for reducing the slippage and increasing the mechanical efficiency and life of deep well pumps.

5 In the said drawings,

Figure 1 is a view in vertical section of the lower end of my improved pump;

Figure 2 is a view in vertical section of the upper end of said pump;

10 Figure 3 is a view in section seen on a line 3-3 of Figure 1;

Figure 4 is a view in section seen on a line 4-4 of Figure 2.

15 In the pump illustrated, there is provided an equivalent for the usual hollow plunger in what I term the plunger tube 7. Said tube is carried by a reduced end 8 of a plunger head 9. Co-axially of the plunger tube there is provided an outer tube 10 which is carried directly by the plunger head and which is of such internal diameter as to provide an annular space 11 between its inner perimeter and the inner tube. The provision of the annular space, and the manner in which oil is caused to flow therein, forms one of the salient features of my invention. The plunger head is divided, as at 12, and is provided with an annular series of vertical bores 14 which lead from the 20 annular space 11 upwardly and outwardly, as at 15, to points externally of the plunger head. Each of the said bores is provided with a seat 16 on which a ball 17 reposes. Pins 18 permit of the balls raising a slight 25 distance only. The plunger head is hollow and screws directly onto a common working valve cage 19 which is provided with the usual ball 20.

30 The external diameter of the outer tube is such that it may pass upward through common tubing such as 21. The pump includes a large diameter casing 22 which is incorporated in the string of tubing by means of special couplings 23 and 24. Coupling 23 is of reduced diameter as at 25 to provide a lead or guide for the plunger when it is being inserted in the casing, although not so shown in the drawing for want of space. Coupling 23 is arranged at 35 about the same elevation as the plunger head when the plunger is in extreme uppermost pumping position. In other words, when the plunger is raised to the end of its normal up-stroke, it is still practically contained within the casing.

40 In conformance with a salient feature of my invention, coupling 24 is provided with an elongated taper seat 27. Upon this seat there normally reposes a hollow taper plug 28 having a through bore 29 providing a valve seat 30. A ball 31 reposes on the valve seat 30 and said ball and plug co-act to take the place of the common standing valve. A pin 32 limits the upward movement of the ball. The taper plug is also

employed to carry a vertical tube 33 which is hereinafter termed the pump barrel, inasmuch as it serves in the place of the usual pump barrel in co-action with the plunger to provide for periodically increasing and decreasing the volume existing between the standing valve and the working valve. The pump chamber has no function other than to serve as an enlarged member of a string of tubing so that the space 34, intermediate 75 of the casing and outer plunger tube, may be subject at all times to the full hydrostatic pressure of the fluid column extending up through the tubing. It should be noted here that an annular area of the plug, indicated by 35, and external to the standing tube 33, is constantly subject to such pressure. Under usual pumping conditions the oil level is well below the surface of the ground and is often only slightly above the 80 pump. Therefore, the force acting to hold the plug upon its seat will be considerably in excess of the pressure acting from below. This pressure difference is depended upon to some extent to hold the plug upon its 85 seat, although it will be apparent that the slight taper of the plug and seat provides for a very effective frictional hold. The metal of the coupling member 24, where the taper bore begins, is beveled as at 36, to encourage sand gravitating into and through the taper bore when the plug is removed; all for a purpose hereinafter apparent. The lower end of the inner plunger tube is provided with a valve seat element 36' forced 100 therein. Upon said element a ball 37 rests, the upward movement of which is limited by a pin 38. The ball and seat member act to provide a valve adjacent the extreme lower end of the plunger to increase the effectiveness of the plunger in the presence of gas, as will be explained later.

105 Inasmuch as some of the objects of the invention are to facilitate removal, repair and replacement of the parts, I will first 110 describe the manner of installing the pump and subsequent removal of parts for inspection, repair and replacement.

115 The pump casing and couplings 23 and 24 are incorporated in the string of tubing so that the pump casing may be lowered to the required depth with the tubing above it acting to provide a fluid course for the oil raised by the pump. The taper plug and standing tube may be installed correctly in the casing before it is lowered, if desired. After the pump casing and tubing are properly lowered and set the plunger may be sent down through the tubing in the usual manner. The enlarged lower end 40 of the outer tube will guide the plunger and preclude its becoming caught in the joints on the way down. When said end reaches coupling 23 it will become centrally located 120 thereby with regard to the standing tube, so 125

that the outer tube will pass over the standing tube without interference.

For inspection or repairs, the plunger (inner tube, outer tube and plunger head) 5 may be removed through the tubing as a unit without disturbing the tubing. To remove the standing valve, a suitable tool or grab (not shown) is lowered to catch the transverse pin provided in the standing tube. 10 The taper plug may then be jarred loose from its seat and raised, together with the tube. Similarly, it may be returned and driven into place on the seat by dropping it a suitable distance or by means of jars (not 15 shown), such methods being thoroughly understood by those skilled in the art.

In considering the actual operation of the parts in pumping, particular consideration must be given to the fact that a slight clearance exists as at 41 and 43 between the standing tube and the outer and inner plunger tubes, respectively. This clearance I have found may be quite substantial, such as $\frac{3}{2}$ of an inch. In fact, the drawings are quite 20 close to scale as regards the clearances and thicknesses of the tubes. As the plunger reciprocates the annular space above the standing tube will increase and decrease accordingly in volume, and such increase and 25 decrease of volume will result in a certain pumping action through the small valves contained in the plunger head.

In considering the action of the complete pump, let us assume an instance where the 30 pump is at such a depth that the hydrostatic pressure within the pump casing is 1,000 pounds per square inch, while the fluid level in the well is such that the pressure in the tubing below the standing valve is 35 500 pounds per square inch. At the moment of inertia of the plunger, the force acting to hold the plug upon its seat will be twice that of the pressure acting from below and a net pressure of 500 pounds per square inch 40 will be acting downwardly on said plug. When the plunger is descending, the net force acting to hold it down will be even greater slightly. When the plunger is moving upward, that area of the plug lying 45 within the standing tube will have no appreciable downward pressure, while the pressure from below will be fully effective. The pressure from below, however, may even 50 then be overbalanced by virtue of the fact 55 that the annular area of the plug externally of the standing tube is subject to 1,000 pounds per square inch. Proper portioning of the areas mentioned will provide for an excess pressure acting to hold the plug down 60 even during the up-stroke of the plunger. I have avoided mentioning suction in describing the operation of the pump, as it 65 might be misleading. The actual suction effect or suction pressure of this pump during the up-stroke would be the difference be-

tween the practically negligible pressure above the standing valve and the full pressure of the column of fluid which is externally of the tubing and which acts upwardly from below the pump. In other words, the 70 suction of my pump under the conditions above assumed would be 500 pounds per square inch.

Since the pump casing is actually a part of the tubing, the space externally of the 75 plunger and standing tube is subject to the maximum hydrostatic pressure. During the down stroke of the plunger, the pressure within the standing tube and plunger is slightly greater than it is externally of the 80 tubing. Therefore, during the down-stroke there can be no slippage or leakage back into the pump. The conditions existing during the down-stroke will be discussed further 85 hereinafter, it being necessary to first explain conditions during the up-stroke of the plunger. Immediately the plunger rises, the space existing between the lowermost plunger valve and the standing valve increases, and the pressure therein of course drops almost instantly to a negligible quantity. It is during the up-stroke that all single-acting 90 hollow-plunger pumps leak so badly. In my pump, obviously, oil will tend to rush into the clearance between the outer plunger 95 tube and the standing tube. Such oil does not, however, get into the interior of the standing tube, for the following reasons: As the plunger ascends the annular space 100 above the standing tube increases in volume with the result that oil leaking through the clearance will not build up a back pressure in said annular space, and in spite of such leakage the pressure in the annular space 105 may be less than, and is invariably not appreciably greater than the slight pressure in the standing tube during such up-stroke. Therefore, the oil which leaks into the increasing annular space will stay there as 110 there is little or no pressure difference acting to force it further. The oil which always exists between the inner plunger tube and the standing tube will not escape during the up-stroke because, as I have just explained, 115 the pressure in the annular space is then closely approximate to the pressure within the standing tube. Such oil provides a constant seal for the pump.

During the down stroke of the pump, it is obvious and well known that the pressure 120 within the standing tube and plunger will be slightly in excess of the maximum pressure in the tubing and pump casing. Therefore, should any oil tend to flow up between the inner tube and the standing tube it 125 would increase the efficiency of the pump rather than decrease it, and such oil would finally reach points externally of the plunger. However, during such down-stroke the annular space above the standing 130

tube is decreasing. The oil which leaked therein is now displaced upward through the small check valves and outward to the place from which it originally leaked.

5 Such returning oil tends to keep the annular space and the clearances washed of sand. During the down-stroke the upper end of the standing tube may be said to co-act with the two tubes to provide a small pump, 10 which pumps the oil in the annular space back to where it came from and assures the existence of a fluid seal at all times both internally and externally of the standing tube. It is a well known fact that the flow 15 through a small annular clearance is limited and is very much reduced by any appreciable viscosity such as is peculiar to the heavy constituents of crude oil. During the pumping action of the standing 20 tube and annular space, there is even a tendency for some of the oil which can not travel out through the small check valves to travel down between the standing tube and the inner plunger tube.

25 In fact, it will be apparent that the throttling effect of the small check valves and the usual throttling effect of the working valve may be so balanced that the oil seal between the inner tube and the standing 30 tube will remain practically motionless and unchanged during the entire down-stroke.

It is a very extraordinary characteristic 35 of my pump that during the down-stroke there can be no leakage from the pump casing into the tubes whatever by way of the clearances, and during the up-stroke there is little or no leakage because of the constant increase of the annular space above 40 the standing tube.

I do not go so far as to state, as others have done in the art of fluid pumps, that I have obviated slippage entirely. I merely 45 claim to have provided a pump in which the pressure and velocity of the inrushing oil is foiled and arrested in the annular space so that there is not apt to be any slippage into the pump plunger. This arrested slippage is merely forced back where it came 50 from. In other words, I avoid the use of packing, take advantage of the viscosity of the oil for sealing, and take care of any oil that starts to leak into the plunger by pumping it back to where it came from 55 before it can get into the inner tube. Naturally the displacement efficiency of my pump, measuring over the area of the inner plunger tube, will be close to 100 per cent 60 when the valves are tight and the pump is operated at correct speed.

While I have shown and described a specific embodiment of my invention, I do not limit myself to any specific construction or arrangement of parts, and I may alter 65 the construction and arrangement of parts

as I desire or as occasion requires without enlarging the scope of my invention, within the appended claims.

What is claimed is:

1. In a pump, a single-walled member and a double-walled member relatively reciprocal and providing an internal central fluid space and an elongated annular space externally coaxial to said fluid space and separated therefrom, a check valve for said single-walled member, a check valve in said double-walled member at one end of said central fluid space, said double-walled member having discharge passages leading from said central fluid space and said annular space, 70 one of said discharge passages extending through the end of said double-walled member and the other extending laterally through the side of said double-walled member to the exterior thereof. 75

2. In a pump, a single-walled member and a double-walled member relatively reciprocal and providing an internal central fluid space and an elongated annular space externally coaxial to said fluid space and separated therefrom, a check valve for said single-walled member, a check valve in said double-walled member at one end of said central fluid space, said double-walled member having a discharge passage leading from 80 said central fluid space to the exterior of the pump and a discharge passage leading from said annular space to the exterior of the pump, one of said discharge passages extending laterally through the side of said 85 double-walled member, and a check valve controlling the passage from said annular space. 90

3. In a pump, a single-walled member and a double-walled member relatively reciprocal and providing an internal central fluid space and an elongated annular space externally coaxial to said fluid space and separated therefrom, a check-valve for said single-walled member, a check valve in said double-walled member at one end of said central fluid space, said double-walled member having a discharge passage leading from 95 said central fluid space through the end of said double-walled member and a discharge 100 passage leading outwardly through the side of said double-walled member, and a check valve in each of said discharge passages. 105

4. In a pump, a single-walled member and a double-walled member relatively reciprocal and providing an internal central fluid space and an annular space externally coaxial to said fluid space and isolated therefrom, an upwardly-opening non-return valve for said single-walled member, an upwardly-opening non-return valve in said double-walled member at one end of said central fluid space, said double-walled member having a discharge passage leading from 110 the other end of said central fluid space to 115 the exterior thereof. 120

125

130

the exterior of the pump and forming with said central fluid space a fluid course, and a leakage discharge passage leading from said annular space to the exterior of the pump 5 at a point remote from the fluid course, said leakage discharge passage and its outlet being entirely isolated from said fluid course, whereby discharge from said leakage discharge passage is effected independently of 10 the flow from said fluid course.

5. In a pump, a single-walled member and a double-walled member relatively reciprocal and providing an internal central fluid space and an annular space externally co- 15 axial to said fluid space and isolated there- from, an upwardly-opening non-return valve

for said single-walled member, an upwardly-opening non-return valve in said double-walled member at one end of said central fluid space, said double-walled member hav- 20 ing a discharge passage leading from the other end of said central fluid space to the exterior of the pump and forming with said central fluid space a fluid course, a leakage discharge passage leading from said annular space to the exterior of the pump at a point remote from the fluid course, said leakage discharge passage and its outlet being entirely isolated from said fluid course, and a 25 check valve controlling said leakage dis- 30 charge passage.

IRWIN B. WINSOR.

- the exterior of the pump and forming with said central fluid space a fluid course, and a leakage discharge passage leading from said annular space to the exterior of the pump
- 5 at a point remote from the fluid course, said leakage discharge passage and its outlet being entirely isolated from said fluid course, whereby discharge from said leakage discharge passage is effected independently of
- 10 the flow from said fluid course.
5. In a pump, a single-walled member and a double-walled member relatively reciprocal and providing an internal central fluid space and an annular space externally co-
- 15 axial to said fluid space and isolated therefrom, an upwardly-opening non-return valve
- for said single-walled member, an upwardly-opening non-return valve in said double-walled member at one end of said central fluid space, said double-walled member having a discharge passage leading from the other end of said central fluid space to the exterior of the pump and forming with said central fluid space a fluid course, a leakage discharge passage leading from said annular space to the exterior of the pump at a point remote from the fluid course, said leakage discharge passage and its outlet being entirely isolated from said fluid course, and a check valve controlling said leakage discharge passage.

IRWIN B. WINSOR.

DISCLAIMER.

1,621,046.—*Irwin B. Winsor*, Los Angeles, Calif. DEEP-WELL PUMP. Patent dated March 15, 1927. Disclaimer filed February 18, 1929, by the assignee by mesne assignments, *Joseph G. Richardson*.

Hereby disclaims from claim 1 of said Letters Patent No. 1,621,046:

“In a pump, a single-walled member and a double-walled member relatively reciprocal and providing an internal central fluid space and an elongated annular space externally coaxial to said fluid space and separated therefrom, a check valve for said single-walled member, a check valve in said double-walled member at one end of said central fluid space, said double-walled member having discharge passages leading from said central fluid space and said annular space, one of said discharge passages extending through the end of said double-walled member and the other extending laterally through the side of said double-walled member to the exterior thereof.”

And your petitioner disclaims from claim 5 of said Letters Patent No. 1,621,046:

“In a pump, a single-walled member and a double-walled member relatively reciprocal and providing an internal central fluid space and an annular space externally coaxial to said fluid space and isolated therefrom, an upwardly-opening non-return valve for said single-walled member, an upwardly-opening non-return valve in said double-walled member at one end of said central fluid space, said double-walled member having a discharge passage leading from the other end of said central fluid space to the exterior of the pump and forming with said central fluid space a fluid course, a leakage discharge passage leading from said annular space to the exterior of the pump at a point remote from the fluid course, said leakage discharge passage and its outlet being entirely isolated from said fluid course, and a check valve controlling said leakage discharge passage.”
